UNITED STATES PATENT OFFICE.

FRANK T. DICKINSON, OF CHICAGO, ILLINOIS.

MOLD.

1,043,809.

Specification of Letters Patent. Patented Nov. 12, 1912.

Application filed November 2, 1907. Serial No. 400,411.

To all whom it may concern:

Be it known that I, FRANK T. DICKINSON, a citizen of the United States, residing at Chicago, in the county of Cook and State of Illinois, have invented certain new and useful Improvements in Molds, of which the following is a specification.

The invention relates to molds and particularly to those designed for casting of brake shoes.

The invention has for its principal objects; the provision of a mold having improved means for securing the proper relative hardness in various portions of the article produced, and the provision of a simple form of mold capable of producing a brake shoe having the most desirable distribution of chilled and soft wearing surfaces.

Certain embodiments of the invention as applied to molds for brake shoes are illustrated in the accompanying drawings, wherein:

Figure 1 is a longitudinal section through the center of an empty mold, Fig. 2 is a diagrammatic face view of a brake shoe cast in the mold of Fig. 1 after such brake shoe is worn to a point corresponding to the line *a—a* in Fig. 1; Fig. 3 is a transverse section through the lower half of the mold of Fig. 1, with a shoe in position therein, the section being taken at a position corresponding to the line *b—b* in Fig. 1, Fig. 4 is a longitudinal section through a modified form of mold, Fig. 5 is a detail of the insert used in the form of mold shown in Fig. 4, Fig. 6 is a longitudinal section through another form of mold, and Figs. 7, 8, 9, 10 and 11 are diagrammatic views showing the various ways in which the chill may be distributed over the face of the shoes by the use of non-conducting material in the roughened surfaces of the mold in which the shoes are cast. Fig. 12 is a transverse section through the lower half of the mold of Fig. 1, with a shoe in position therein, the section being taken at a position corresponding to the line *d—d* in Fig. 1; and Fig. 13 is a transverse section through the lower half of the mold of Fig. 4, with a shoe in position therein, the section being taken at a position corresponding to the line *c—c* of Fig. 4.

The mold as shown in Fig. 1 for casting brake shoes, comprises an upper sand cope,

and a lower metal drag, in which the main portion of the casting is carried. The sides of the metal mold member or drag are provided with three recesses, which recesses carry the sand inserts 1, 2 and 3, so that the side surfaces of the mold consists partly of sand and partly of metal. When the shoe is cast all those portions in the lower mold member are chilled with the exception of the side surfaces of the shoe adjacent the inserts 1, 2 and 3, and such portions of face of the shoe as are sufficiently near to the sand inserts to be effected thereby. When a shoe is cast in this mold the entire wearing face may have a high chill and consequently be quite hard, or it may be modified as hereinafter set forth, but as the shoe is worn down it will soon be worn into the regions adjacent the inserts 1, 2 and 3 where the cooling of the casting was slower, and the wearing face of the shoe will be correspondingly modified as indicated diagrammatically in Fig. 2, which shows the face of the shoe after the shoe has been worn down to a point corresponding to the line *a—a* in Fig. 1. The parts marked 5 having been adjacent inserts 1, 2 and 3 are softer than the parts marked 4, which were adjacent the metal edges of the mold, and of course the influence of the sand inserts is greater at the edges of the shoe, so that the hardness of the metal in the face of the shoe between the parts marked 5 increases as the distance from the edges increases. By this means a wearing face is secured having areas of hard metal to prolong the life of the shoe and areas of softer metal to increase the frictional qualities of the shoe. It will also be seen that as the shoe wears further and further the proportion of hard and soft metal varies for the reason that the areas of the modifying inserts 1, 2 and 3 vary.

Fig. 3 illustrates the shoe in the metal mold, on the line *b—b* of Fig. 1, the portion 8 indicating the hard surface of the shoe and the portion 16 indicating the softer interior. If desired the surface 13 may be made corrugated as indicated in Fig. 1, and provided with a fire-proof material of low conductivity such as a mixture of fire clay, plumbago and banana oil, or other refractory materials with a suitable binder. This arrangement will modify the chill on the wearing face of the mold, and if desired, the corrugations and refractory material

may be arranged in configurations A, A¹, A², A³ and A⁴ such as those indicated in Figs. 7, 8, 9, 10 and 11, whereby a portion of the face of the shoe is allowed to be chilled and the remainder protected from rapid cooling by means of the refractory material, and rendered less hard than the other portions of the face. The coating in the corrugations may be made very thin, dependent upon the softness of the metal desired, and in some cases may constitute merely a wash or spray containing the refractory material.

A modified form of mold is shown in Fig. 4. The construction here illustrated 15 differs from that of Fig. 1 in that a soft iron insert 11 is used adjacent the face of the shoe, and instead of the inserts 1, 2 and 3 the insert 9 is provided, constituting a portion of the upper mold member. The portions marked 10 are the metal sides of the lower mold member, and the arrangement secures a chilling of the surfaces of the shoe at the end with the central portion softer by reason of the sand sides 9.

25 In Fig. 6 still another modification is shown, the end portions 12 corresponding to the portions 10 in Fig. 4, but the insert shown in Fig. 4 being omitted in this form of device. The surface 13 is preferably 30 corrugated and may be provided either with a continuous covering of refractory material corresponding to that in the device of Fig. 1, or the refractory material may be arranged over the surface in the form of one of the 35 configurations shown in Figs. 7, 8, 9, 10 and 11. In this form of mold the ends of the shoe cast are chilled by reason of the metal side portions 12, while the central portion is rendered softer by reason of the 40 sand sides, and by reason of the refractory material used upon the corrugated surface 13. In this form of mold, as well as that of Figs. 1 and 4, the harder portions of the face of the shoe are adjacent the center of 45 the shoe, while the edges of the shoe are modified and rendered softer by reason of

the sand portions of the mold adjacent the edges of the shoe.

Having thus described my invention and illustrated its use, what I claim as new and 50 desire to secure by Letters Patent is the following:

1. A mold comprising a metal mold member having a surface partially covered by a thin coating of a refractory material of low 55 conductivity.

2. A mold comprising a metal mold member having a surface partially covered by a wash of a refractory material of low conductivity.

60 3. A mold comprising a metal mold member having a surface partially covered by a thin coating of a refractory material of low conductivity; that portion of the surface carrying the said material being roughened 65 to retain it.

4. A mold comprising a metal mold member having a surface provided with a roughened portion only partially covering it and adapted to retain a coating of material of 70 low conductivity.

5. A mold for brake shoes comprising a metal mold member having in the side thereof a sand insert of varying cross section from the bottom to the top of the side, 75 whereby the chill in the face of the shoe decreases from the center to the side of the shoe and the character of the wearing surface of the shoe varies as it is worn away.

6. A mold for brake shoes comprising a 80 mold member having a roughened metal surface for forming the wearing face of the shoe, and a coating of refractory relatively non-conducting material partially covering such surface.

85 In testimony whereof I have hereunto signed my name in the presence of the two subscribed witnesses.

FRANK T. DICKINSON.
